COLLAPSIBLE STOOL OR TABLE

Henry S. Leggett, Brooklyn, N. Y.

Application February 14, 1951, Serial No. 210,918

6 Claims. (Cl. 155—136)

1

This invention relates to a new and improved collapsible stool or table.

One object of the invention is the provision of such a device which is of sturdy construction and yet is foldable into a compact unit for carrying purposes, which may be made in many sizes varying from a stool for small children to be used around the house to large stools for general use, especially for picnics, sporting events, etc. and in still larger dimensions to be used as a table for most any eventuality.

Another object of the invention is to construct the device in such manner that one stroke of the operating means folds or unfolds the device.

Another object of the invention is to construct the device in such manner that when it is unfolded it is automatically locked in such condition.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a plan view of the device in unfolded condition.

Fig. 2 is a side elevational view of the device in unfolded condition.

Fig. 3 is a side elevational view of the device in folded condition.

Fig. 4 is a fragmentary perspective view from beneath of the top portion of the device.

Fig. 5 is an enlarged sectional view on line 5—5 of Fig. 2, with certain parts left out for clarity.

Fig. 6 is an enlarged fragmentary sectional view on line 6—6 of Fig. 2.

Fig. 7 is a sectional view on line 7—7 of Fig. 6.

Fig. 8 is an enlarged fragmentary sectional view on line 8—8 of Fig. 4.

Referring now to the drawings, the device comprises a center post 10 atop which is secured a disc 11. Both the post 10 and the disc 11 are here shown as made of wood, but it will be understood that any other sturdy material may be utilized. Pivottally mounted in a depression 12 in the top face of disc 11 is a handle 13 by which the device is folded and unfolded as presently will be described.

Secured to the under side of disc 11 by means of a plurality of hook eyes 14 is a metal ring 15 about which the inner ends of a plurality of radial rods 16 are looped as at 17. Pivottally secured to each rod 16 by means of hook eyes 18

are a pair of matched segments 20, the hook eyes 18 extending from the rods into the under sides of the adjacent edges of the associated pair of segments as best illustrated in Fig. 4. The segments 20 are located so that their inner edges substantially abut the peripheral edge of disc 11.

A ring 21 is secured on the post 10 a short distance below the disc 11 by means of hook eyes 22. Pivottally secured on the ring 21 by means of loops 23 at their inner, downwardly offset ends are a plurality of radially extending rods 24. Each rod 24 extends between the edges of the proximate segment 20 of adjacent pairs of said segments and is pivottally secured to said proximate segments by means of hook eyes 25.

Each rod 24 engages in the bore 26 of a connector 27 which is looped through a suitable hole in the upper end of a bar 28. The bars 28 are provided at their lower ends with hook eyes 30 which engage a ring 31 which surrounds the post 10. It is to be mentioned that if desired the ring 31 may be replaced by a tube or sleeve. Also engaging the ring 31 are four hook eyes 32 which are secured in the upper ends of bars 33. The bars 33 extend downward alongside of the post 10 and near their lower ends are interconnected by four fixtures 34, each of which is formed as shown in Figs. 6 and 7. The fixtures 34 are secured to the bars by means of hook eyes 35 whose shanks extend through the stock of the former. Each fixture 34 is in the form of a metal strip whose ends are curled slightly to conform to the cross-sectional configuration of the bars 33, and which, between the bars 33 arcs inward toward the post 10, the said inward arc being to a much greater degree at the top of the strip than at the bottom. An inclined arcuate guideway 36 is thus provided.

Adapted to the guideways 36 are four legs 37 which are connected to the post 10 at their upper ends by means of interengaged hook eyes 38 and 40. The lower end of each leg 37 is bevelled as at 41 to permit the same lying securely on the floor when the leg is in the extended position of Fig. 2. In order to retain the legs 37 in the guideways 36 a strong wire loop 42 has its ends secured to the hook eyes at either side of the guideway and embraces the leg.

The loop 42 may be made of any strong material to form a suitable bracket structure.

The construction is such that when the device is in the the unfolded position of Figs. 1 and 2, the segments 20 form with the disc 11 a table top or stool which is supported by the bars 28, said bars in turn being supported by the bars 33

which are held up by the legs 37 through the loops 42. Thus the device is automatically locked in unfolded position by the attempt of its own weight to spread the legs 37. To fold the device, all that is required is to grasp the ring 31 in one hand and the handle 13 in the other and move the two components apart. This action moves the ring 31 downward along the post 10, folding the legs 37 against the post and pulling the bars 28 inward toward the post. The movement of the bars 28 causes the segments 20 of each pair to fold together about their connecting rod 16, and toward the post 10 due to the differential pivoting of the rods 16 and 24. To reopen the device the above procedure is actuated in reverse.

In view of the above it will readily be seen that the ring 31 may advantageously be replaced by a sleeve or tube if desired.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A folding table or stool which comprises a center post, a disc atop said post, a handle recessed into the upper face of said disc, a ring supported from and beneath said disc, a second ring supported on the post a short distance below the first said ring, a plurality of radial rods having their inner ends pivotally anchored on the first said ring, a matched pair of segments pivotally connected at their proximate edges to each said rod, the inner ends of the segments substantially abutting the peripheral edge of the disc, a plurality of second rods extending radially from said second ring and having their inner ends pivotally secured thereto, said second rods being pivotally connected each to the proximate edges of the proximate segments of adjacent pairs, a plurality of bars each having its upper end slidably connected to a second rod, a ring surrounding said post and to which the lower ends of said bars are connected, four bars having their upper ends connected to the last said ring and extending downward alongside of said post, brackets interconnecting the lower ends of the last said bars, four legs pivoted at their upper ends to said post between the last said bars and engaging said brackets, and a loop connected to each bracket and securing the associated leg thereagainst.

2. A folding table or stool which comprises a center post, a disc atop said post, a handle recessed into the upper face of said disc, a ring supported from and beneath said disc, a second ring supported on the post a short distance below the first said ring, a plurality of radial rods having their inner ends pivotally anchored on the first said ring, a matched pair of segments pivotally connected at their proximate edges to each said rod, the inner ends of the segments substantially abutting the peripheral edge of the disc, a plurality of second rods extending radially from said second ring and having their inner ends pivotally secured thereto, said second rods being pivotally connected each to the proximate edges of the proximate segments of adjacent pairs, a plurality of bars each having its upper end slidably connected to a second rod, a ring surrounding

said post and to which the lower ends of said bars are connected, four bars having their upper ends connected to the last said ring and extending downward alongside of said post, brackets interconnecting the lower ends of the last said bars, four legs pivoted at their upper ends to said post between the last said bars and engaging said brackets, and a loop connected to each bracket and securing the associated leg thereagainst, each said bracket consisting of a metal strap extending between the bars and having the portion between the bars arcing inward to fit a said leg, said arc being inclined outward as it extends downward.

3. A folding table or stool which comprises a center post, a disc atop said post, a handle recessed into the upper face of said disc, a ring supported from and beneath said disc, a second ring supported on the post a short distance below the first said ring, a plurality of radial rods having their inner ends pivotally anchored on the first said ring, a matched pair of segments pivotally connected at their proximate edges to each said rod, the inner ends of the segments substantially abutting the peripheral edge of the disc, a plurality of second rods extending radially from said second ring and having their inner ends pivotally secured thereto, said second rods being pivotally connected each to the proximate edges of the proximate segments of adjacent pairs, a plurality of bars each having its upper end slidably connected to a second rod, a ring surrounding said post and to which the lower ends of said bars are connected, four bars having their upper ends connected to the last said ring and extending downward alongside of said post, brackets interconnecting the lower ends of the last said bars, four legs pivoted at their upper ends to said post between the last said bars and engaging said brackets, and a loop connected to each bracket and securing the associated leg thereagainst, each said bracket consisting of a metal strap extending between the bars and having its center portion arcing inward to form a downwardly and outwardly inclined guideway for a said leg.

4. A folding table or stool which comprises a center post, a disc atop said post, a handle recessed into the upper face of said disc, a ring supported from and beneath said disc, a second ring supported on the post a short distance below the first said ring, a plurality of radial rods having their inner ends pivotally anchored on the first said ring, a matched pair of segments pivotally connected at their proximate edges to each said rod, the inner ends of the segments substantially abutting the peripheral edge of the disc, a plurality of second rods extending radially from said second ring and having their inner ends pivotally secured thereto, said second rods being pivotally connected each to the proximate edges of the proximate segments of adjacent pairs, a plurality of bars each having its upper end slidably connected to a second rod, a ring surrounding said post and to which the lower ends of said bars are connected, downward movement of the last said ring folding the segments of each pair against one another and all of the pairs toward said post, four bars having their upper ends connected to the last said ring and extending downward alongside of said post, brackets interconnecting the lower ends of the last said bars, four legs pivoted at their upper ends to said post between the last said bars and engaging said brackets, and a loop connected to each

bracket and securing the associated leg thereagainst.

5. A folding table or stool which comprises a center post, a disc atop said post, a handle recessed into the upper face of said disc, a ring supported from and beneath said disc, a second ring supported on the post a short distance below the first said ring, a plurality of radial rods having their inner ends pivotally anchored on the first said ring, a matched pair of segments pivotally connected at their proximate edges to each said rod, the inner ends of the segments substantially abutting the peripheral edge of the disc, a plurality of second rods extending radially from said second ring and having their inner ends pivotally secured thereto, said second rods being pivotally connected each to the proximate edges of the proximate segments of adjacent pairs, a plurality of bars each having its upper end slidably connected to a second rod, a ring surrounding said post and to which the lower ends of said bars are connected, downward movement of the last said ring folding the segments of each pair against one another and all of the pairs toward each post, four bars having their upper ends connected to the last said ring and extending downward alongside of said post, brackets interconnecting the lower ends of the last said bars, four legs pivoted at their upper ends to said post between the last said bars and engaging said brackets, and a loop connected to each bracket and securing the associated leg thereagainst, each said bracket consisting of a metal strap extending between the bars and having its center portion arcing inward to form a downwardly and outwardly inclined guideway for a said leg.

6. A folding table or stool which comprises a center post, a disc atop said post, a handle recessed into the upper face of said disc, a ring supported from and beneath said disc, a second ring supported on the post a short distance below the first said ring, a plurality of radial rods having their inner ends pivotally anchored on the first said ring, a matched pair of segments piv-

otally connected at their proximate edges to each said rod, the inner ends of the segments substantially abutting the peripheral edge of the disc, a plurality of second rods extending radially from said second ring and having their inner ends pivotally secured thereto, said second rods being pivotally connected each to the proximate edges of the proximate segments of adjacent pairs, a plurality of bars each having its upper end slidably connected to a second rod, a ring surrounding said post and to which the lower ends of said bars are connected, downward movement of the last said ring folding the segments of each pair against one another and all of the pairs toward each post, four bars having their upper ends connected to the last said ring and extending downward alongside of said post, brackets interconnecting the lower ends of the last said bars, four legs pivoted at their upper ends to said post between the last said bars and engaging said brackets, and a loop connected to each bracket and securing the associated leg thereagainst, upward movement of the last said ring drawing said legs upward and inward against said post through said brackets, each said bracket consisting of a metal strap extending between the bars and having its center portion arcing inward to form a downwardly and outwardly inclined guideway for a said leg.
